UNITED STATES PATENT OFFICE.

RICHARD JOCHIMSEN AND BRUNO HENZE, OF NEW YORK, N. Y.

UNIVERSAL WASHLINE.

Application filed January 19, 1926. Serial No. 82,189.

This invention relates to laundry devices and more particularly to means for supporting articles while drying and airing.

One of the main objects of the invention is to provide means for allowing articles gripped in independent devices to freely pass around sprockets or other rotary means in such manner as enabling the conveyor to be loaded with wash along its entire length and;

10 A further feature is to provide a plurality of dependent clothes engaging devices at fixed intervals on the chain to hang pendant for conveniences in securing articles, thus eliminating the inconvenience of clothes directly contacting with the line avoiding one of the chief causes of entanglements of articles draped over a line in the usual manner.

These and other objects, which will become apparent as the specification progresses, are accomplished by the novel construction, combination and arrangement of parts herein-after described and shown in the accompanying drawing, forming a material part of this disclosure, and in which:—

25 Figure 1 is a side elevational view showing the device in position connected to a wall.

Figure 2 is a partial bottom plan, partial sectional view, the section being taken on line 2—2 of Fig. 1.

30 Figure 3 is a side elevational view of the chain showing the location of the hooks carrying clothes pins.

Figure 4 is a detailed view of the clothes pin.

35 Figure 5 is a detailed view of the links shown in Figure 3 drawn to an enlarged scale.

Figure 6 is a similar view showing the manner in which the hook carrying links are connected to the links.

40 Figure 7 is a fragmentary sectional view taken on line 7—7 of Figure 2, drawn to an enlarged scale.

In the drawing, the numeral 10 generally designates a metal plate secured to a wall adjacent a window having rigidly attached to it a preferably triangularly shaped post 11.

45 Removably engageable on the post 11 is a metal frame 12 having a triangularly shaped head 13 and arms 14 bent to form parallel portions 15.

Mounted at the ends of the portions 15 are pins 16 passing therethrough and set in a wooden block 17 to pivotally hold the same in position; the pins having slots near their outer ends to engage with washers 18. 55

Rigidly secured in the block or support 17 by pins 19 acting as keys is a plurality of shafts 20 having rotatably mounted on them sprocket wheels 21, 22 and 23. The shafts 20 have slots 24 near their outer ends, the hubs 60 25 of the sprocket wheels being made to abut against the block 17 by washers 26 removably engageable in the slots 24.

Passing over the teeth 27 of the wheels 21 and 23 and engaging therewith is an endless 65 chain or conveyor 28 guided by the teeth of the wheel 22. The chain, preferably made of aluminium to prevent rust and diminish weight, consists of links 29 and 29' shown in detail, in Figures 3 and 5. 70

Positioned at spaced intervals on the chain 28 and formed from one end of the links 29' are hooks 30 as best seen in Figure 6.

Removably engageable with the hooks 30 are clothes pins consisting of a metal loop 31 75 having secured to it, two spring arms 32 bent at their ends to engage in the sides of two wooden blocks 33 having undulated interengageable inner surfaces 34.

In operation, the blocks 33 are separated, 80 an end of a garment is placed therebetween, and the blocks allowed to snap back in position, thus effectively gripping the same.

By means of the loop 31, the clothes pin is then hung on the hook 30 of the chain 28; 85 whereupon the chain is manually moved to allow the garment to take a position in the open court for drying or airing.

From the foregoing it may be seen that a single garment can be readily removed from 90 the line, without disturbing the position of other garments also suspended from the line.

Although considerable detail has been gone into in describing the invention, it is purely descriptive and illustrative, not limitative, as 95 obviously many minor changes may be made in details of construction without departing from the spirit and scope of the appended claim.

Having thus described our invention, what 100

we claim as new and desire to secure by Letters Patent, is:—

In a wash line, a horizontal support, sprockets removably arranged on said support, an endless conveyor chain carried and guided by said sprockets in a horizontal plane, and spaced hooks integrally formed on

certain of the links of said conveyor chain adapted to engage carrying devices.

In witness whereof we have signed our names.

RICHARD JOCHIMSEN.
BRUNO HENZE.
